CANDLESTICK

Henry Pachico, Concord, Calif.

Application May 4, 1953, Serial No. 24,817

Term of patent 3½ years

(Cl. D48—2)

To all whom it may concern:

Be it known that I, Henry Pachico, a citizen of the United States of America, residing in the city of Concord, county of Contra Costa, State of California, have invented a new, original, and ornamental Design for a Candlestick, of which the following is a specification, reference being had to the accompanying drawing, forming a part hereof, wherein:

The dotted lines indicating a candle in Figure 3 are for illustrative purposes only.

I claim:

The ornamental design for a candlestick, substantially as shown and described.

HENRY PACHICO.
